UNITED STATES PATENT OFFICE.

BENJAMIN LIPPER, OF PHILADELPHIA, PENNSYLVANIA, ASSIGNOR TO HIMSELF, AUGUSTUS A. LAZARUS, AND ISAAC A. SCHWARZ, OF SAME PLACE.

DESIGN FOR TRIMMING.

SPECIFICATION forming part of Design No. 23,979, dated January 29, 1895.

Application filed December 28, 1894. Serial No. 533,229. Term of patent 3½ years.

To all whom it may concern:

Be it known that I, BENJAMIN LIPPER, a citizen of the United States, residing in Philadelphia, Pennsylvania, have invented a new and original Design for Trimming, of which the following is a specification.

My design for trimming is fully shown in the accompanying drawing which represents a face view of a piece of the trimming.

10 The design comprises the close top band *a*, the open or lacework band *b*, the interrupted band *d*, and the shell like projecting ornaments *f*, the tops of which serve to interrupt

the continuity of the band *d*, these shell like ornaments being crossed by a band *g*. 15

I claim—

The design for trimming, substantially as described and shown.

In testimony whereof I have signed my name to this specification in the presence of 20 two subscribing witnesses.

BENJAMIN LIPPER.
